(57) CLAIM

The ornamental design for a face mask, as shown and described.

DESCRIPTION

FIG. 1 is a front perspective view of the face mask showing my new design;

FIG. 2 is a front perspective view of the face mask of FIG. 1, showing an open front flap according to an alternate view; FIG. 3 is a front view of the face mask of FIG. 1;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines depict portions of the face mask that form no part of the claimed design.
